US0D1036204S

(12) **United States Design Patent** (10) **Patent No.:** **US D1,036,204 S**
(45) **Date of Patent:** **** Jul. 23, 2024**

(54) **CONTAINER**

(71) Applicant: **BottleKeeper, LLC**, Houston, TX (US)

(72) Inventor: **Matthew T. Campbell**, Cave Creek, AZ (US)

(73) Assignee: **BottleKeeper, LLC**, Houston, TX (US)

(**) Term: **15 Years**

(21) Appl. No.: **29/830,619**

(22) Filed: **Mar. 14, 2022**

Related U.S. Application Data

(63) Continuation of application No. 29/707,603, filed on Sep. 30, 2019, now Pat. No. Des. 945,832, which is a continuation of application No. 29/669,218, filed on Nov. 6, 2018, now Pat. No. Des. 866,270, which is a continuation of application No. 15/584,013, filed on May 1, 2017, now Pat. No. 10,118,735, which is a continuation of application No. 15/362,540, filed on Nov. 28, 2016, now Pat. No. 9,637,270, which is a continuation of application No. 14/153,688, filed on Jan. 13, 2014, now Pat. No. 9,505,527.

(74) *Attorney, Agent, or Firm* — Quarles & Brady LLP

(57) **CLAIM**

The ornamental design for a container, as shown and described.

DESCRIPTION

FIG. 1 is a front, bottom perspective view of a container showing the new design;

FIG. 2 is a front elevational view thereof;

FIG. 3 is a left side elevational view thereof; and,

FIG. 4 is a bottom plan view thereof.

The dash-dash-dash broken lines are included for the purpose of illustrating portions that form no part of the claimed design.

1 Claim, 3 Drawing Sheets
